United States Patent Office.

MATTHEW H. FOSTER AND HUBERT C. HART, OF UNIONVILLE, CONNECTICUT.

Letters Patent No. 77,476, dated May 5, 1868.

IMPROVED NUT-MAKING MACHINE.

The Schedule referred to in these Letters Patent and making part of the same.

TO ALL WHOM IT MAY CONCERN:

Be it known that we, MATTHEW H. FOSTER and HUBERT C. HART, of Unionville, in the county of Hartford, and State of Connecticut, have invented certain new and useful Improvements in Machine for Making Nuts; and we do hereby declare that the following is a full, clear, and exact description thereof, reference being had to the accompanying drawings, and to the letters of reference marked thereon, which form a part of this specification, in which—

Figure 1 is a perspective, showing the cutter in the act of severing the nut.

Figure 2, a perspective, representing the punch down.

Figure 3, a perspective of the reversed side of the machine, showing the mode of operating the formers.

Figure 4, a perspective of the block detached.

Figure 5, a perspective, exhibiting the manner of constructing and operating the cutter.

Figure 6 is a section of the block, showing the mode of operating the punch; and

Figure 7 is a plan, showing the formers in position when not in operation.

The nature of this invention consists, first, in the employment of a movable or sliding bed for conveying the nut from the cutter to the punch and die; second, in the employment of formers, operating substantially in the manner hereafter specified; and, third, in the combination of the cutter and punch, operating substantially as will be hereinafter set forth.

To enable others skilled in the art to make and employ our machine, we will now describe its construction and operation.

A represents the main bed, furnished with a longitudinal dove-tail chamber, in which is fitted and slides bed-piece or carriage B. At each end of the main bed, A, are secured the supports C-C, upon which the shaft D has its bearings, said shaft being retained in position by boxes, in the usual way. E is the driving-wheel or pulley, and F the cam-grooved wheel, by means of which motion is communicated to the movable bed or carriage B. Both of these wheels are located on shaft D, in the position shown in figs. 1 and 2.

a, b, c, d, and e represent five cams, arranged also on shaft D, as seen in the same figures. The peculiar offices of these cams will be fully apparent hereafter.

G represents a metal button, which works in the cam-shaped groove in wheel F. This button is so secured to carriage B, that it will revolve when the wheel is in motion, thus avoiding the rubbing friction which would otherwise occur. By means of this device, motion is communicated from wheel F to movable bed-piece or carriage B.

f f' represent two metal formers, working at right angles to each other, as seen in figs. 3 and 7. Former f slides beneath the casing h, which is secured to the carriage, as shown in figs. 2 and 3. Each of these formers is supplied with springs, i i', which force them back in their original position, when relieved from pressure.

I represents a lever, pivoted to the carriage, one end resting against the outer end of former f', while its opposite end is turned up at right angles and bevelled on one of its sides, as fully shown in fig. 3.

k is a stiff metal plate, secured upon the periphery of wheel F. This metal plate is so bent or formed that in the revolution of the wheel it will engage the lever I, and thus make it operate former f'. k' also represents a metal plate, secured to the inner side of wheel F, (see fig. 3.) The lower inner side of this plate is bevelled, and by it the former f is operated. It should be particularly observed that the relative position of both of these plates should be such as to work both of the formers at the same time.

k'' represents a metal bar, secured to the main bed A. k³ is likewise a metal bar, secured to bed A immediately opposite former f'. The object of both of these bars will be more apparent hereafter.

x represents a shallow concave metal die, on carriage B, fig. 7.

O designates a solid block, shaped and stepped as shown in figs. 4 and 6. This block is firmly secured to the bed A, so that its stepped end will be just beneath the shaft D, or under cams a, b, c, d, and e. This end

of the block is provided with two vertical slots, in which the slide *m* and cutter *n* work, as fully seen in figs. 1 and 4.

o o' represent springs, which assist in pressing up the cutter and slide, when relieved of cams *b* and *d*. It will be observed that both the cutter and punch *p*, which work in slide *m*, as seen in fig. 6, are provided with a notch or slot, in which rest lifters 1 and 2. These lifters are set in small shafts, one of which is seen in fig. 5. On the end of said shafts are cams, *s s'*, (see fig. 4.) The object of these cams is to throw up the cutter and punch when they have been pressed down by cams *b* and *d*. It will be remarked that the cam *d* is a triple one, the two outside ones acting upon the slide, while the centre one operates the punch, fully shown in figs. 1 and 2.

t represents a metal set, at the bottom of slide *m*. This set has a hole through it, sufficiently large to allow the punch to work freely.

W represents a guide, for conducting the metal to the cutter.

The operation of our machine is as follows: Motion is given to the shaft *D* by means of a band passing over wheel *E*. As the wheel *F* revolves, motion is imparted to the movable bed by the circular button working in the cam-shaped groove while the cutter is up. The metal from which the nuts are to be cut is pushed in guide *W*. The cutter *n* now descends and severs the blank, when it falls into die *x*. The formers now being operated upon by the metal plates *k k'*, come together, and, with the metal bars *k'' k'''*, form a square box, thus giving the nut the desired shape. The slide now descending, presses the blank into the concave die, and then follows the punch and drives a hole through it. The nut, as soon as relieved from the punch and slide, is pushed out of the concave die by the former *f*. The next nut, being operated upon in the same manner, forces the preceding one forward in the groove, and so on until it falls from the machine.

Having thus fully described our invention, what we claim as new, and desire to secure by Letters Patent, is—

1. Sliding bed *B*, having button *G* and pivoted lever *I* thereon, with cam-wheel *F*, provided with studs *k k'*, all constructed and arranged substantially as described.

2. We claim arranging the cams *a b c d e s s'* so as to operate the cutter *n*, slide *m*, and punch *p*, substantially as set forth.

3. The improved nut-machine, consisting of mechanism constructed, combined, and arranged substantially as herein set forth.

In testimony that we claim the foregoing as our own, we affix our signatures in presence of two witnesses.

MATTHEW H. FOSTER,
HUBERT C. HART.
